JOINT STRUCTURE FOR WIRE DISPLAY RACKS

Harry J. Rubenstein, Kansas City, Mo.

Application October 25, 1950, Serial No. 192,643

4 Claims. (Cl. 211—106)

1

This invention relates to display racks for articles of merchandise formed in its entirety from wire or rod stock and having a plurality of pockets formed to permit insertion and removal of the merchandise supported thereby without damage to the articles and without undue difficulty particularly in the removing operation.

It is the most important object of the present invention to provide a wire display rack having a plurality of article supporting assemblies mounted on a common frame therefor in stepped arrangement and each including a pair of vertical rods that diverge as the lowermost ends thereof are approached, the rods having lateral extensions thereon for connection with the support next adjacent thereto in such manner as to not interfere with the removal of the articles.

Another object of the present invention is to provide article supports of the aforementioned character each of which has a forwardly extending leg on the lowermost end thereof and a laterally extending arm that joins with the forward support at the back of the latter so as to not extend into the pocket of the adjacent support and thereby interfere with easy removal of the articles of merchandise and loading the pockets when such becomes necessary.

More minor objects will be made clear or become apparent as the following specification progresses, reference being had to the accompanying drawing, wherein:

Figure 1 is a front elevational view of a wire display rack made in accordance with my present invention and showing the joint structure thereof.

Fig. 2 is a side elevational view of the display rack.

Fig. 3 is an enlarged, fragmentary, side elevational view similar to Fig. 2.

Fig. 4 is an enlarged, fragmentary, cross-sectional view taken on line IV—IV of Fig. 3; and

Fig. 5 is a fragmentary, side elevational view, parts being broken away for clearness.

The supporting frame for the plurality of article supports shown in the drawing includes a continuous, substantially U-shaped wire length having a pair of spaced-apart substantially parallel frame members 10 and 12 that are disposed at an angle in the manner illustrated in Fig. 2 of the drawing. The lowermost ends of the frame members 10 and 12 terminate in substantially vertical lengths 14 and 16 respectively and substantially horizontal portions 18 and 20 respectively.

A horizontal bight portion 22 underlying the

2

frame members 10 and 12 interconnects portions 18 and 20. The frame members 10 and 12 are interconnected by a plurality of spaced, horizontal cross-bars 24 and a pair of cross-bars 24' and 24''. Each cross-bar 24 has an article support broadly designated by the numeral 26 rigidly secured thereto. Supports 26 are identical and are formed from a single length of wire-like material presenting a horizontal bight member 28, a pair of depending spaced-apart vertical rods 30 and a forwardly extending horizontal leg 32 on the lowermost end of each rod 30 respectively. Each leg 32 is in turn provided with a laterally extending arm 34.

As most clearly illustrated in Fig. 1, of the drawing, the lowermost ends of the rods 30 terminate in stretches 36 that converge slightly as the legs 32 thereof are approached. Consequently, the distance between the lowermost ends of stretches 36 is less than the length of the bight members 28. The arms 34 on the outermost free ends of forwardly extending horizontal legs 32, extend outwardly from the legs 32 in a substantially horizontal plane and connect directly with the corresponding rods 30 of the article support 26 next forwardly thereof and adjacent the line of bend between rods 30 and stretches 36.

It is noted that the vertical rods 30 of all of the article supports 26 are disposed along the back of the corresponding cross-bars 24 and join therewith intermediate the ends of rods 30 and above the corresponding connection with arms 34. Because of the inclination of the frame members 10 and 12, the article supports are therefore disposed in a step-like arrangement with the bight members 28 progressively higher as the uppermost ends of frame members 10 and 12 are approached. The uppermost bight member 28 conveniently serves as a means for hanging the entire display rack upon a wall 38 or the like through the medium of suitable hooks or other fastening elements 40.

A plurality of pockets are accordingly presented between the rods 30 of article supports 26 for receiving cards, pamphlets, books or the like 42. Cross-bars 24' and 24'' have parallel legs 58 of a U-shaped member 52 secured thereto as shown in Fig. 5, member 52 being disposed forwardly of the lowermost support 26, presenting a pocket therewith, and having the proximal arms 34 secured thereto. The lowermost edge of the articles 42 rest directly upon the forwardly extending horizontal legs 32. It is seen that by the disposition of arms 34 at the back of the support 26 to which they are connected, there

will be no interference with loading of the pockets with articles 42 and particularly arms 34 will not interfere with removal of articles 42 or damage the same as such removal takes place.

This novel arrangement improves substantially over the conventional joint structures wherein fastening ends such as at 34 extend into the proximal pocket and not only interfere with removal of the articles 42 but oftentimes tear or scratch the same because of a sharp end that is presented when the wire stock is cut for subsequent bending operations.

It is contemplated of course, that the cross-bars 24, 24' and 24'' be spot-welded directly to the frame members 10 and 12 and that the article supports 26 be joined with the cross-members 24 and with the article supports next forwardly thereof by spot-welding.

It is also apparent that while only one series or row of article supports has been illustrated, a number of rows thereof might be provided by extending the lengths of cross-bars 24 and providing a suitable number of angularly disposed frame members such as at 10 and 12 for further reinforcing the entire supporting frame structure.

Having thus described the invention, what is claimed as new and desired to be secured by Letters Patent is:

1. A display rack comprising a spaced pair of angularly disposed frame members; a plurality of horizontal cross-bars joining said frame members; and an article support for each cross-bar respectively, each support including a spaced pair of vertical rods secured to corresponding cross-bars and converging at the lowermost ends thereof, each of said ends being provided with a laterally extending leg joined with the proximal rod of a support next adjacent thereto.

2. A display rack comprising a plurality of article supports; and means for mounting said supports in terraced arrangement, each support comprising a pair of spaced, vertical rods having the lowermost ends thereof in converging relationship, each rod being provided with a leg 45

extending toward the support next below, each leg having a laterally extending arm joined with the proximal rod of said support next below.

3. A display rack comprising a plurality of identical article supports each including a horizontal member, a pair of spaced vertical rods depending from said member and having the lowermost ends thereof in converging relationship, and a laterally extending leg on said end of each rod, respectively; and means for mounting said supports with the upper ends of the rods of each support parallel with the upper ends of the rods of the other supports and with said members in terraced arrangement, each leg being joined with the proximal rod of the support next below.

4. A display rack comprising a plurality of identical article supports each including a horizontal member, a pair of spaced vertical rods depending from said member and having the lowermost ends thereof in converging relationship, a laterally extending leg on said end of each rod, respectively, and an outwardly extending arm on each leg, respectively; and means for mounting said supports with the upper ends of the rods of each support parallel with the upper ends of the rods of the other supports and with said members in terraced arrangement, each arm being joined with the proximal rod of the support next below.
